UNITED STATES PATENT OFFICE

EDWARD H. WILLIAMS, OF CRAFTON, PENNSYLVANIA, ASSIGNOR TO THE NATIONAL SUPPLY COMPANY, OF TOLEDO, OHIO, A CORPORATION OF OHIO

PACKING SLEEVE FOR OVERSHOTS

Application filed September 21, 1928. Serial No. 307,383.

My invention relates to packings for overshots or fishing tools for broken drill pipes through which a forced circulation of a fluid, such as muddy slush fluid, is kept up during 5 drilling operations. When such drill pipes are twisted apart, circulation of the slush fluid through the pipes naturally ceases, and the mud settles out of the slush fluid and shale may fall in around the drill pipes, soon 10 causing them to become stuck and very difficult to free. If the circulation of fluid can be re-established around the broken drill pipes, there is usually little or no difficulty in removing them from the wells, as the solidified mud is restored to a solution and the circulation of the fluid carries the shale upward and out of the well holes to the slush pits.

It is the object of this invention to provide an improved packing for overshots or fishing 20 tools whereby the circulation of fluid may be re-established through an overshot and down through the broken drill pipe in the well hole and upwardly around the drill pipe, the packing forming a fluid-tight fit between the 25 overshot and the drill pipe. More specifically, it is one object of this invention to provide a cylindrical resilient packing sleeve slidable within the overshot and having at its bottom end an inwardly and upwardly 30 extending annular flange resembling a truncated cone and provided with a central opening through which fluid may pass down from the overshot and into the drill pipe.

Referring to the accompanying drawings, 35 Fig. 1 is a central vertical section of the lower end of an overshot fishing tool in operative connection with a broken drill pipe, one of my packing sleeves being shown in central vertical section and in operative connection 40 with the broken-off end of a drill pipe. Fig. 2 is a similar view but some of the lower portions shown on Fig. 1 are broken away and the packing sleeve is shown operatively connected with the coupling, at the upper end 45 of which the drill pipe has been broken off. Fig. 3 is a view similar to the upper portion of Fig. 1, but showing a drill pipe more completely filling the cross-section of the overshot than the drill pipes in Figs. 1 and 2. 50 Fig. 4 is a view similar to Fig. 3 but showing

the packing sleeve resting on the coupling instead of on the end of the broken-off drill pipe. Fig. 5 shows a modification of the packing sleeve shown in Figs. 1 to 4, one-half being shown in side elevation and the other 55 half in central vertical section.

Referring to Figs. 1 and 2, I show an overshot fishing tool comprising the pipe or shank 1 extending to the top of the well and having a shoe 2 screwed on its lower end. This shoe 60 has a number of upwardly and inwardly projecting spring fingers 3 attached at their lower ends to the shoe by the screws 4, but free at their upper ends. I show two lengths 5 and 6 of a drill pipe connected together by 65 the coupling 7. The length 5 is shown broken off at some distance above the coupling. The portion of the drill pipe above the break is supposed to have been removed and the fishing tool has been lowered so that its lower 70 end has telescoped the broken pipe, the fingers 3 having passed below the coupling and snapped inwardly against the pipe length 6. If the shank 1 is pulled upwardly the fingers 75 3 will engage the lower end of the coupling 7 and pull the broken drill pipe upwardly out of the well unless the drill pipe has become "frozen" or stuck in the well hole, as hereinbefore described.

I provide a cylindrical packing sleeve 8 80 composed of a flexible resilient material, such as rubber, whose diameter is substantially the same as the internal diameter of the shank 1. The sleeve has at its bottom an inwardly and upwardly extending flange 9 in the form of 85 substantially a truncated cone which is provided centrally at its top with the opening or orifice 10. Normally the flange 9 will have the undistorted shape shown in Fig. 2. The lower end of the sleeve is somewhat 90 thickened forming an annulus 11 whose inner annular face 12 converges upwardly, the inner face of the said flange being a continuation of the face 12.

When the fishing tool is lowered into a 95 well as described, it has therein a sleeve 8. When the spring fingers 3 have passed below the coupling 7, fluid circulation is re-established by pumping it down the pipe or shank 1. The traveling fluid forces the sleeve 100

8 down in Fig. 1 until it engages the broken end of the pipe length 5 where it becomes lodged, the annulus 11 becoming wedged fluid-tight between the shank 1 and the pipe length 5 while the interior of the bottom of the sleeve becomes distorted by being forced partly down over the end of the pipe length 5 with the orifice 10 over the passage through the drill pipe. The pressure of the circulating fluid distorts the flexible resilient sleeve so as to prevent the passage of the fluid between the shank 1 and the sleeve and also between the pipe length 5 and the sleeve. Normal circulation of the fluid is thus re-established, whereby the mud settled from the previously standing circulating fluid, and the shale accumulated around the drill pipe are carried to the surface of the well in the usual manner. The broken drill pipe may then be pulled out of the well in the usual manner.

In Fig. 2 the pipe length 5 is broken off so short that the sleeve 8 is caused to seat on the upper end of the coupling 7. The sleeve is in Fig. 2 shown in its natural or undistorted shape. When the circulation of fluid is established, it will be more or less distorted, but the orifice 10 will remain practically central over or in the drill pipe and the lower end of the sleeve 8 will effectually seal the space between the shank 1 and the coupling 7.

In Fig. 3, the sleeve 8 occupies the same position as in Fig. 1, but the space between the shank 1 and the pipe length 5 is narrower, causing the annulus 11 to be distorted into a more cylindrical form, the upper end of the flange about the orifice catching over the end of the pipe length 5, as in Fig. 1, and holding the sleeve in place.

In Fig. 4, the pipe length is broken off so as to let the sleeve seat directly on the coupling 7 which has substantially the same diameter as the shank. The sleeve in Fig. 4 is shown in its undistorted condition. When the circulating fluid flows down through it, it becomes distorted but provides an effectual seal between the shank and the coupling.

Fig. 5 shows a modified form of packing sleeve, marked 8^a. The parts marked 9, 10, 11 and 12 are as in Figs. 1 to 4. The sleeve 8^a has a short distance above its bottom an external upwardly and outwardly extending flange 13. There is an annular series of openings or orifices 14 near the upper end of the sleeve and at both sides of this series of openings is the external annular rib 15 and between the flange 13 and the rib 15 is an annular series of openings 16. The flange 13 and the rib 15 form lines of friction contact between the sleeve and the shank, whereby the sleeve will slide down more freely to its contact with the coupling or pipe length end than it would slide if the entire external cylindrical surface of the sleeve engages the shank. The openings 14 and 16 are for

equalizing the fluid pressure between the inner and outer surfaces of the sleeve.

I claim—

1. In combination an overshot for a pipe, the overshot having a relatively long upwardly extending hollow shank, a cylindrical resilient packing sleeve slidable within the shank forming a seal between the periphery of the sleeve and the inner wall of the shank, said sleeve having at its bottom end an inwardly and upwardly extending annular flange in the form of a truncated cone and a central circular opening through which a fluid may pass into the pipe. 70
75

2. In combination an overshot for a pipe, the overshot having a relatively long upwardly extending hollow shank, a cylindrical resilient packing sleeve slidable within the shank, said sleeve having at its bottom and an inwardly and upwardly extending annular flange in the form of a truncated cone and a central circular opening through which a fluid may pass into the pipe, the sleeve having an annular external projecting portion in engagement with the inner surface of the shank. 85
90

3. In combination an overshot having a relatively long upwardly extending hollow shank, a cylindrical resilient packing sleeve slidable within the shank, said sleeve having at its bottom end an inwardly and upwardly extending annular flange in the form of a truncated cone and a central circular opening through which a fluid may pass, the sleeve having external annular ribs, there being openings through the sleeve between the ribs. 95
100

4. In combination an overshot for a pipe, the overshot having a relatively long upwardly extending hollow shank, a cylindrical resilient packing sleeve slidable within the shank, the periphery of the said sleeve being adapted at all positions of the sleeve in the shank to seal the annular space between the pipe and the said shank and having a portion adapted to lie over the upper end of the pipe and also having an opening through which fluid may pass into the pipe. 105
110

5. In an overshot, a hollow shank slidable longitudinally downwardly over a pipe with a free upper end, a fixed support for the pipe, and a cylindrical resilient packing sleeve slidable within the shank above the support and forming a seal between itself and the inner wall of the shank and having at its bottom end an inwardly and upwardly extending annular flange in the form of a truncated cone and a central circular opening through which a fluid may pass into the pipe, the inner face of the truncated cone forming a seal between itself and the said end of the pipe. 115
